UNITED STATES PATENT OFFICE

110,600

DESIGN FOR A SHOE

Roy Maling, West Roxbury, Mass.

Application June 9, 1938, Serial No. 77,682

Term of patent 7 years

To all whom it may concern:

Be it known that I, Roy Maling, a citizen of the United States, residing at West Roxbury, in the county of Suffolk and State of Massachusetts, have invented a new, original, and ornamental Design for a Shoe, of which the following is a specification, reference being had to the accompanying drawing, forming part thereof.

In the drawing:

The figure is a side elevation of a shoe showing my new design. The design is substantially the same on both sides of the shoe.

The essential feature of the invention resides

in the heel with prominent grooves extending approximately parallel to each other and to the face of the heel lift, the heel portions between the grooves having contrasting surface aspect. As the design is applicable to shoes of various shapes and styles, the representation of shoe is conventional, for showing an application of the design.

I claim:

The ornamental design for a shoe, as shown and described.

ROY MALING.
